INVENTOR

Ira Hungerford,

BY *Richard Aver.*

ATTORNEY

UNITED STATES PATENT OFFICE.

IRA HUNGERFORD, OF MILROY, INDIANA.

ANIMAL-RESTRAINING DEVICE.

1,259,402.

Specification of Letters Patent. Patented Mar. 12, 1918.

Application filed August 3, 1917. Serial No. 184,819.

To all whom it may concern:

Be it known that I, IRA HUNGERFORD, a citizen of the United States, residing at Milroy, in the county of Rush and State of Indiana, have invented certain new and useful Improvements in Animal-Restraining Devices, of which the following is a specification.

This invention relates to certain new and useful improvements in tools for catching and holding animals for the purpose of performing ringing, branding or other like operations.

The primary object of this invention is to provide a tool of this character which can be manipulated with one hand to securely hold an animal and thus enables the operator to have the free use of the other hand to perform the ringing or other operation.

Another object of the invention is to provide a tool of the character described which has the clamping parts thereof so arranged that the same will be caused to grip the animal with increasing firmness as the latter pulls away in an endeavor to escape.

A further important object of the invention is to provide a tool of the above described general character which is constructed of a few simple parts easily manufactured and assembled, thus providing a strong and durable device which is readily operated and can be placed on the market at a minimum cost.

The above and other objects and advantages of this invention will be in part described and in part understood from the following description of the present preferred embodiment, the same being illustrated in the accompanying drawings, in which,

Figure 1 is a perspective view of my improved device.

Fig. 2 is a sectional view showing the application thereof.

My improved catching and holding tool includes a jaw frame 1 to which is pivotally secured a U shaped loop or mouth piece 2. The jaw frame 1 comprises a curved bridge or nose piece 3 from which extend the parallel side members 4. At a point remote from the nose piece 3 these side members are curved upwardly as indicated at 5, inwardly as at 6, and the free ends thereof are then flattened and again extended in spaced parallelism to provide the extensions 7. A handle is indicated at 8 and is pro-

vided at one end with a hand grip 9. The opposite end of the handle is hooked as indicated at 10 and is adapted to be pivotally secured between the extensions 7 by means of a pivot bolt 11, the hooked end of the handle extending beyond the pivot point and adapted to be engaged by a stop 12 connecting the extensions 7 at a point spaced from the pivot bolt 11.

The mouth piece or loop 2 is preferably formed of a single piece of metal bent into U form to provide the bit 13 and the spaced side members 14. The free ends of these side members 14 are adapted to be flattened and pivotally secured to the sides 4 of the jaw frame as indicated at 15.

My invention although capable of general use is more especially adapted for catching and holding hogs while being ringed. In using the tool the bit 13 is placed in the animal's mouth and as the latter following its natural instinct pulls away and throws its head toward the ground in an endeavor to escape, the bridge piece 3 will be brought to bear firmly against the nose of the animal. The flexible connection between the handle and the jaw frame is to enable the operator to more conveniently retain his grip on the handle when the animal lowers his head in an endeavor to free itself. The stop bolt 12 holds the jaw frame in a straight line with the handle when inserting the bit 13.

It is understood that the foregoing discloses only a preferred embodiment of my invention and that I may resort to such minor changes in the construction, proportion and arrangements of the several parts thereof as are desired, providing of course that such changes come within the scope of the appended claims and are not a departure from the spirit of the invention.

What I claim is:

1. A tool for catching and holding animals, including a handle, a clamp pivotally secured thereto, a stop carried by said clamp and adapted to be engaged with said handle, and a mouth piece pivotally secured to said clamp.

2. A tool for catching and holding animals including a handle rod, a clamping frame including spaced side members having their free ends pivoted to said handle rod, a stop carried by said side members and engageable with the handle to limit movement of the clamping frame in one

direction, and a second clamping frame pivotally secured to the side members of the first mentioned frame.

3. A tool for catching and holding animals, including a handle, a clamp comprising a longitudinally grooved nose piece, side members extending in spaced parallelism from said nose piece and having their free ends pivotally secured to said handle, a transverse pin carried by said side members and engageable with the handle to limit the movement of the frame in one direction, a second clamping frame including a bit adapted to be inserted in the animal's mouth and having its end bent into parallelism for pivotal engagement with the side members of said first mentioned frame.

4. A tool for catching and holding animals including a handle, a clamp comprising a nose piece, side members extending in spaced parallelism from said nose piece, the ends of said side members being curved upwardly and inwardly for pivotal engagement with said handle, and a mouth piece including a bit, parallel side members integral with said bit and adapted to be pivotally secured to said clamp.

5. A tool for catching and holding animals including a handle having a hooked

end, a jaw frame comprising a nose piece, side members extending in spaced parallelism from said nose piece, the ends of said side members being curved upwardly and inwardly and then again extending in spaced parallelism to provide a pair of flattened extensions adapted to be pivotally secured to said handle adjacent the hooked end thereof, a stop carried by said extensions for engagement with the hooked end of said handle, and a U shaped loop having its side members pivotally secured to said jaw frame adjacent the nose piece thereof.

6. A tool for catching and holding animals including a handle, a jaw frame pivotally secured to said handle adjacent one end thereof, a stop carried by the jaw frame and engageable at times with the end of said handle to limit swinging movement of the jaw frame in one direction, and a mouth piece pivotally secured to said jaw frame for clamping coöperation therewith.

In testimony whereof I affix my signature in presence of two witnesses.

IRA HUNGERFORD.
